COMBINATION PLUG-IN RESISTOR AND SWITCH

Donald Francis Hastings, Fairlawn, N. J., assignor to Hardwick, Hindle, Inc., Newark, N. J.

Application August 18, 1937, Serial No. 159,697

9 Claims. (Cl. 201—48)

This invention relates to a combination plug-in resistor and switch, in which the resistor and switch portions are relatively adjustable, one with respect to the other, whereby the output voltage from the device may be adjusted to meet the requirements of the apparatus which is connected to the device.

It is the principal object of my invention to provide what may be termed a relatively simple and compact plug-in resistor and switch which will act as a line voltage reducer for use in connection with appliances of different types and in which, in some cases, speed changes may be desirable.

Other ancillary objects will appear on reading the specification taken in connection with the annexed drawing, wherein:

Figure 1 is an elevational view of the completely assembled device, on a reduced scale.

Figure 2 is a vertical, sectional view on an enlarged scale through the device shown in Figure 1, the view being taken at right angles to the plane of the paper.

Figure 3 is a plan view of the top of Figure 2.

Figure 4 is a view on the line 4—4 of Figure 2.

Figure 5 is a view on the line 5—5 of Figure 2.

Figure 6 is a view on the line 6—6 of Figure 2.

Figure 7 is an elevational view of the resistor per se.

Figure 8 is a diagram of the circuit arrangement through the resistor and switch.

In the various views, wherein like numbers refer to corresponding parts, 1 is a resistor composed of a suitable core portion 2 of porcelain or some other high heat-resisting material, on which 35 is placed a winding embedded in a slip 3 of vitreous material which is baked after the winding is put in position. In the drawing no attempt has been made to show the winding, but taps 4 are indicated as coming therefrom.

40 The resistor 1 is mounted between two circular-shaped discs 5 and 6 which are preferably of suitable insulating material. This mounting includes a pair of clamps 7 and 8 preferably of metal and somewhat cup-shaped, so that the cup portion 45 thereof fits within the hollow portion of the resistor shell 2. Between the clamps 7 and 8, and the member 5, there is positioned a spacing member 9, preferably of strong insulating material, such as hard fiber, and through this and the

50 members 7 and 8 passes a bolt 10 having a head 11 set in a recess in the member 5. The opposite end of the bolt 10 is threaded and a nut 12 is seated on the threaded portion to draw the clamp 8 against the end of the core 2. The member 5 carries a 55 pair of contact members 13 and 14. As shown,

the members 13 and 14 are somewhat U-shaped, the arms passing through holes 15 and 16 in the member 5, while the bottom of the U portions lie in grooves in the outer face of the member 5. The other arms of the U-shaped members pass inwardly through holes provided in the member 5 and are adapted to be attached in any satisfactory manner, as by soldering or spot-welding to connectors 17 and 18 which extend to the taps 4 on the resistor 1.

Placed over the top of the insulator 5 is another insulator 19 which may be fastened thereto in any satisfactory manner as by screws 20. The member 19 has slots 21 therein which are in alignment with the slots 15 and 16 in the member 5, so that a plug attached to a supply cord coming from the device to be operated by the electric current may be inserted through these slots or openings into engagement with the contact members 13 and 14. On the insulator 6 are mounted a plurality of contact members 22 which are preferably in the form of eyelets as shown in Figure 2 and which have projections or fingers 23 which are bent inwardly and pass through openings 24 for the purpose of making electrical engagement with the taps 4 on the resistor 1. These connections may be made in any satisfactory manner as by soldering or welding. The connections to the taps 4 may likewise be made by soldering or welding.

To prevent the clamp 8 from contacting with the inner faces of the eyelets 22, there is a washer 25 of high heat-resisting material such as mica. Positioned closely adjacent the disc 6 is a terminal plate 26 to which is attached a pair of contact prongs or plugs 27. One end of the plugs 27 is 30 counter-bored to give the effect of an eyelet which is spun over at 28 to clamp the plugs securely to the insulator 26. Positioned in the hollow or counter-bored portion of the plugs 27 are springs 29 which are adapted to press against balls 30 40 which thus act as contact members for electrical engagement means between the plugs 27 and the eyelets 22 on the disc 6. The co-action between the eyelets 22 and the balls 30 acts to form a positive switch-positioning means.

45 Positioned in the terminal plate 26 is a bushing 31 which acts as a bearing for the bolt 10. The inner end of the bushing 31 engages the disc 6 so that when the nut 32 on the bolt 10 is drawn up, the discs 5 and 6 are held in operated position and 50 the resistor unit, including the resistor 1 and the discs 5 and 6 with cooperating contacts, is held in resilient contact engagement with the balls 30.

55 Enclosing the resistor 1, is a casing member 33 preferably having a plurality of ventilating holes 55

34 therein. The casing member 33 may be formed by rolling up a piece of metal which has been perforated as explained, and then passing over the ends thereof collars or bands 35 and 36 5 which preferably are of metal and act to hold the shell 33 in position. The collars 35 and 36 are fastened to the member 33 in any satisfactory manner as by riveting, welding or some equivalent means.

10 As shown in Figure 2, one end of the casing member 33 embraces the disc 5, while the opposite end rests against the disc 6 and the collar 36 preferably engages the inner face of the terminal plate 26 so that it may act as an out-board guide 15 or support for the resistor unit. It will also be noted that the plate 19 overlaps the collar 35, thereby making a more finished appearance of this end of the device. In addition, it will be noted that the disc 19 acts to hold the contact 20 members 13 and 14 in position in their respective slots in the disc 5.

From the construction as described, it will be understood that the resistor with its associated parts, including the casing, forms a unit which 25 is rotatable about the terminal plate 26 so that various taps on the resistor 1 may be connected to the plugs 27 as indicated in the diagram in Figure 8. As shown in this diagram, one portion 30 of the resistor 1 is connected in shunt across the load terminals 13 and 14 at all times. This is desirable for certain types of load such as a dry-shave razor, but for other types of load this shunt resistance may not be required.

To indicate the voltage that the device is set to 35 deliver, I prefer to calibrate the collar 36 with the voltage to be delivered by the device at the different taps as indicated in Figure 1. The manner of making an operating connection between the casing 33 and either the disc 5 or disc 6 may 40 be of any suitable kind. For example, the disc 6 may have a projection which will extend into the space 38 between the edges of the rolled up casing member 33 when the bands 35 and 36 are not used; or the projection may extend into a slot or 45 notch in the band 36 when the bands are used; or a pin may be inserted through one of the perforations into the disc 5.

While I have shown round types of plugs 27, the projecting ends may be rectangular in shape. 50 Furthermore, the collars or bands 35 and 36 may be eliminated entirely by suitably extending one end of the casing 33, if desired, into engagement with the terminal plate 26.

Other details may likewise be varied without 55 departing from the spirit of my invention or the scope of the appended claims.

What I claim is:

1. In a device of the class described, a resistor having a plurality of taps, a pair of discs of insulating material disposed one at each end of the resistor, one of said discs having slots therein, contact members carried by said disc in operative position with relation to said slots so plug terminals inserted through said slots will engage 60 said terminals, the other of said discs having a plurality of contacts arcuately arranged around the axial center of the disc and connected to the taps on the resistor, a terminal plate adjacent the last mentioned disc, terminal plugs carried by said 65 plate in insulating relation one to the other, contact members associated with said plugs for engaging the contacts on said second mentioned disc, and means for rotatably mounting said discs and resistor on said terminal plate.

70 2. A device as set forth in claim 1 further char-

acterized in that the means for rotatably mounting the discs and resistor include the following parts, a clamp at and engaging each end of the resistor, a spacer between the first-mentioned disc and its associated clamp, a bushing located in the terminal plate and engaging the second-mentioned disc, an insulator between the disc and the other adjacent clamp, and a bolt going through said parts for clamping them in operative position.

10 3. A device as set forth in claim 1 further characterized in that the resistor and discs are housed within a perforated casing member composed of a rolled up perforated sheet held together at its opposite ends by circular bands, the one at the 15 terminal plate end engaging the terminal plate and thereby acting as an annular guiding support for the rotatable structure of which it is a part.

20 4. A device as set forth in claim 1 further characterized in that the resistor and discs are housed within a cylindrical casing member one end of which may engage on the second mentioned disc while the other end embraces the first mentioned disc, a circular band at each end of said casing, 25 the band at said terminal plate end having its edge engaging said terminal plate as an annular guide for the rotatable structure.

30 5. A device as set forth in claim 1 further characterized in that the resistor and discs are housed within a cylindrical casing member one end of which may engage on the second mentioned disc while the other end embraces the first mentioned disc, a circular band at each end of said casing, 35 the band at said terminal plate end having its edge engaging said terminal plate as an annular guide for the rotatable structure, and an insulator overlying and fastened to the first-mentioned disc and having slots therein in alignment with the slots in said disc.

40 6. A device as set forth in claim 1 further characterized in that the resistor and discs are housed within a perforated casing member composed of a rolled up perforated sheet held together at its opposite ends by circular bands, the one at the 45 terminal plate end engaging the terminal plate and thereby acting as an annular guiding support for the rotatable structure of which it is a part, said band adjacent the terminal plate bearing indica for indicating the output voltage at 50 which the device is set.

7. A device as set forth in claim 1 further characterized in that the terminal plugs carried by said terminal plate each has a counterbore therein in which a spring and ball is positioned, the balls acting as the contact members to engage the contacts on the second-mentioned disc, the contacts on this disc being eyelets, the said balls being adapted to seat therein thereby positively positioning the switch part of the device in any set position, said eyelets having fingers bent around and through openings in the disc whereby they may be connected to the taps on the resistor.

8. A combination plug-in and resistor and switch including a resistor having a plurality of taps, a casing for the resistor, a pair of internally positioned contact members mounted adjacent one end of the resistor on an insulator forming one end of the casing and adapted to have a plug inserted through openings in the insulator into engagement with the contact member, a pair of external plug members mounted adjacent the opposite end of the resistor on a disc-shaped insulator forming the other end of the casing, a 70 75

plurality of arcuately arranged contacts mounted on another disc-shaped insulator positioned in an adjacent plane parallel to but intermediate the insulator carrying the external plugs and the end of the resistor, means for making resilient engagement between the plugs and said arcuately arranged contacts, and means for attaching the resistor and other parts to the mounting carrying said external plugs so the resistor and associated parts may be rotated on said mounting.

5. A double ended resistor plug switch including, a casing closed at both ends by separate insulating means fastened thereto, the insulating means at one end carrying plug-in contacts and

the insulating means at the opposite end carrying arcuately positioned contact members, an insulator located closely adjacent said last mentioned insulating means, and carrying externally extending plugs with means directly contacting with the inner ends of the plugs for engaging said contact members as the latter are moved across the inner ends of the plugs, a resistor mounted at its ends between said end insulating means and having taps connected to said contact members and means for rotatably mounting the resistor, casing and said insulating means on the insulator carrying the plugs.
